Letters Patent No. 2469. Dated Sept. 25. 1866.

Design for a Floor Oil Cloth Pattern.

The Schedule referred to in the Letters Patent and making part of the same

To all whom it may concern:

Be it known that I John J. Webster of the City County and State of New York, have invented or produced a new and original Design for a Pattern to be printed upon a Floor Oil Cloth in colors similar to those painted on the drawings accompanying this Specification or in other colors substituted in the places of those painted on the drawings herewith; and I do hereby declare that the drawings accompanying this Specification do give and convey to any one skilled in the art of Oil Cloth printing a more defined and thorough description of the nature of my invention than it is in the power of language otherwise to convey, and is sufficient to enable any one skilled in the art of Oil Cloth printing to execute my invention.

What I claim as my invention and desire to secure by Letters Patent is the Design herein annexed for a Floor Oil Cloth, as shown in the drawings accompanying this Specification.
